His ATTORNEY

UNITED STATES PATENT OFFICE

2,392,661

BASE FOR ELECTRIC LAMPS OR SIMILAR
DEVICESAlfred Greiner, Cleveland Heights, Ohio, assignor
to General Electric Company, a corporation of
New York

Application August 10, 1944, Serial No. 548,891

9 Claims. (Cl. 176—32)

This invention relates to envelope and base construction for electrical devices, including lamps and discharge devices which at present generally have vitreous envelopes, and it involves novelty in construction as well as in manufacture. The invention is especially advantageous for devices whose envelopes have tubular necks or end portions, and is hereinafter explained in connection with double-ended tubular discharge lamps of low-pressure positive column type, and particularly fluorescent lamps of this character. The lamps may be either of the general cold-starting type exemplified in U. S. Patent No. 2,114,842 to Inman, or of the present commercial hot-starting type referred to in U. S. Patent No. 2,212,427 to Peters. The invention aims to provide a simple, strong end and base construction and to facilitate both the manufacture and the final basing of the devices. It is very suitable and advantageous for circularly or helically bent lamp tubes.

Various other features and advantages of the invention will appear from the description of species and forms of embodiment, and from the drawing.

In the drawing, Fig. 1 is a side view of a lamp tube equipped with end discs suitable for the purposes of this invention, an intermediate portion of the tube being broken out and omitted and an end disc and an adjacent portion of the tube wall being partly broken away; Fig. 2 is a tilted view of such a lamp tube after it has been coiled; and Fig. 3 is an end view of a tube such as shown in Fig. 1 or in Fig. 2.

Fig. 4 is a tilted side and sectional view of a tube based according to this invention; Fig. 5 is an inside end view of the base shown in Fig. 4; and Fig. 6 shows a section of the tube end, taken as indicated by the line and arrows 8—6 in Fig. 3.

Fig. 7 is a tilted side and sectional view similar to Fig. 4 illustrating a modified construction; Fig. 8 is an end view of the tube end illustrated in Fig. 7; and Fig. 9 shows a section of the tube end, taken as indicated by the line and arrows 9—9 in Fig. 8.

Fig. 10 is a tilted inside end view of a modified base.

As shown in Fig. 1, the lamp comprises a tubular envelope 1 permeable to light or other desired radiation, and usually of vitreous material, such as the soft glass of which fluorescent tubes are commonly made. Mounted across the ends of the tube 1 are thermionic cathodes 2, 2 of suitable coiled or coiled-coil tungsten filament type, preferably activated by being coated or charged with

alkaline earth metal oxide(s), such as a mixture including barium and strontium oxides. With each cathode 2 may be associated the usual unemissive auxiliary anodes 3, 3, preferably formed by the transversely extending ends of current lead-wires 4, 4 between which the filament 2 is connected. The current leads 4, 4 may be sealed through the envelope ends 5, 5 in various ways; as here shown, they are sealed into a pressed seal 6 at the end of a stem tube 7. An inner exhaust tube 8 is shown opening through the seal 6 at one end of the lamp, and extending out through the corresponding stem 7 to a point outside the envelope end 5, where it is sealed off at 9. The envelope 1 may contain a low-pressure atmosphere of starting gas, such as argon at a pressure of 2 to 4 mm. of mercury, and also a vaporizable and ionizable working substance such as mercury. A supply of mercury, which may exceed the amount that will vaporize during operation of the lamp, is indicated by a drop 11 inside the envelope 1, and an internal coating of fluorescent material or phosphor 12 on the envelope walls is also indicated.

As thus far briefly described, the device corresponds essentially to fluorescent tubes already known, this summary description of known features being intended as a background for the description of other features with which the present invention is more especially concerned.

As here shown, the envelope 1 has at its ends projecting shoulders, preferably formed by outward-enlarged apertured central protuberances or bosses 13, 13 on the tube ends 5, 5, which in the present instance consist of sheet metal discs (as of chrome iron, commercially known as "Allegany 55") against which the glass tube ends abut, and to which they are sealed by fusion. These end discs 5 resemble those shown in U. S. Patents Nos. 2,154,550 to White and Johnson and 2,114,842 to Inman, but are flat with the bosses 13 turned outward instead of inward. Besides affording a hold for the attachment of bases as hereinafter described, the shoulders 13, 13 also afford a grip by which the ends of the straight tube 1 can be held to bend the tube (when softened by suitable heat) into a circle or into one or more coil convolutions, as illustrated in Fig. 2.

The stem tubes 7 may be fused and sealed directly to the inner sides of the discs 5 around the openings into the bosses 13, while the envelope tubes 1 are sealed to the inner sides of the discs inside their marginal flanges. Thus the construction differs somewhat from that shown in U. S. Pat-

ent No. 2,154,550 to White and Johnson, which it broadly resembles.

The base 14 shown in Figs. 4 and 5 comprises a cylindrical shell having an end web 15 that carries hollow contact terminals 16, 16 in the form of tubular biposts, and also having an in-turned flange 17 around its end opening or mouth opposite the web, adapted to fit around the neck of a tube end boss 13 and to interlock behind the shoulder and in the constriction afforded by the enlarged head of the boss. To facilitate passing the shell flange 17 over or around the boss 13, the shell is shown with a number of longitudinal slots 18 extending from near the end web through the mouth flange 17, so that the base 14 can be easily and quickly snapped on the boss. As shown in Fig. 4, the current leads 4, 4 extend from inside the tube 1 out through the stem 7 and the apertured boss 13 into the contact terminals 16, 16, to which they are suitably secured and electrically connected. To prevent the base 14 from turning on the boss 13 after it has been snapped on the boss, the base may be antiturningly engaged with the boss or the envelope end 5, as by means of key lugs 19, 19 formed by shearing out tongues of the sheet metal at the top of the boss 13 and bending them back or retroverting them to lie outside the boss and engage in corresponding notches 20, 20 in the flange 17, as more clearly shown in Fig. 6. This not only prevents the lead wires 4, 4 from being brought into contact, but allows of definitely orienting the contact terminals 16, 16 as desired, relative to the tube 1 and its cathodes 2, 2 and to one another. As shown in Fig. 4, the base 14 is a cap-like shell of molded fiber or other insulation having suitable elasticity.

In practice, the leadwires 4, 4 may be threaded through the contact pins or posts 16, 16 before snapping the base 14 on the boss 13, and afterward drawn taut, soldered, brazed, or squeezed fast in the pins, and cut off flush with the ends of the latter.

Figs. 7, 8, and 9 illustrate a modification in which the tube-end shoulder for interlocking engagement in the base 14 is resilient. In the present instance, the resilience is provided by means of a springy wire ring 21 snapped and thus locked in place around the circumferentially constricted base portion of the apertured boss 13, with its ends at opposite sides of a single key lug 19. While this lug 19 might be formed by retroversion of a tongue as in Fig. 6, it is shown in Fig. 9 as formed by merely shearing the tongue out of the sheet metal of the boss 13 near the flat part of the disc 5 and bending or deflecting it outward at its root and also inward nearly to a right angle at mid-length. As shown, the shell of the base 14 is of sheet metal and the insulative end web 15 that carries the biposts 16, 16 is secured in the shell between an internal shoulder and the flanged-in upper edge of the shell, and is keyed fast against turning by inward folds 22 of the sheet metal at the angle of this flange with the shell. The edge of the shell around its mouth is turned or flanged inward at 17 to lock behind the spring ring 21, which can yield slightly to allow of snapping the shell around it. As here shown at 18, some resilient expansion of the shell mouth is also provided for, by slotting the shell (in one place) from its mouth upward nearly to the web 15.

Fig. 10 illustrates a modification of the base shell to provide for keying it against rotation when it is snapped on the boss 13. For this

purpose, the shell wall is slit and pressed inward adjacent its mouth, thus providing opposed square shoulders 23, 23 to engage at opposite sides of the key lug 19 when the base is applied to the tube end shown in Figs. 8 and 9 and snapped around its boss 13 and resilient ring 21. In this case, the resilience of the ring 21 is mainly relied on, since the base shell is not slotted to provide for resilient expansion thereof as in Fig. 7.

In Figs. 6, 7, 8, and 9, and 10, various parts and features are marked with the same reference characters as their homologues in other figures, as a means of dispensing with repetitive description.

What I claim as new and desire to secure by Letters Patent of the United States is:

1. The combination of a vitreous tube with a metal end disc abutting and sealed to the tube end and presenting at its outer side an integral, projecting, apertured boss circumferentially constricted adjacent the disc proper.

2. The combination of a vitreous tube, a metal end disc abutting and sealed to the tube end and presenting at its outer side a projecting boss circumferentially constricted adjacent the disc proper, and a vitreous stem inside said tube having its end sealed to said metal end disc.

3. The combination of a coiled vitreous tube with its ends alongside its intermediate portion and presenting projecting shouldered bosses, and snap-on bases engaged around and interlocked behind the shoulders of said bosses.

4. The combination with a vitreous tube having an end wall with a projecting shouldered boss at its outer side circumferentially constricted adjacent said end wall, of a base comprising a shell resiliently snapped around said boss and interlocked behind its shoulder in said constriction.

5. The combination with a vitreous tube and a metal disc sealed to the tube end and presenting a projected shouldered boss at its outer side circumferentially constricted adjacent said disc proper, of a base comprising a shell engaged around and interlocked with said shoulder, and having contact terminals exposed at the exterior of said base.

6. The combination with a vitreous tube presenting a projecting resilient shouldered boss at its end, of a base comprising a shell snapped around said resilient shoulder and interlocked behind the same.

7. A device of the character described comprising an envelope with an end wall having at its outer side projecting apertured protuberance circumferentially constricted adjacent said end wall, a base comprising a shell engaged around and interlocked with said protuberance, and having hollow contact terminals exposed at the exterior of said base, and current leads extending from inside the envelope out through said apertured protuberance into said contact terminals, and electrically connected to the latter.

8. A device of the character described comprising an envelope with a metal end disc sealed thereto and having a shouldered and apertured external boss, a spring engaged around said boss and interlocked behind its shoulder, a base comprising a shell engaged around said spring and having an inturned edge interlocked behind said spring, and an end wall with contact terminals exposed at its outer side, electric translation means in said envelope carried by said metal end disc, and current leads from said electric trans-

75

lation means extending out through said boss into said contact terminals, and electrically connected to them.

9. A method of fabricating and basing a coiled vitreous tube with its ends close alongside its intermediate portion; which method comprises fusing and sealing the tube ends to abutting metal discs presenting external projecting shoulders and carrying at their inner sides electrical translation means, with current leads extending 10

5 out through the discs; softening the tube, and coiling it as aforesaid by holds on said discs; threading on said current leads hollow contact terminals of bases having shells, and snapping and interlocking the base shells around and behind said disc shoulders; and electrically connecting said contact terminals to said current leads.

ALFRED GREINER.
